UNITED STATES PATENT OFFICE.

ANDREW W. GRAHAM, OF BUFFALO, NEW YORK.

MATCH AND PACKET THEREFOR.

1,286,877.

Specification of Letters Patent.

Patented Dec. 3, 1918.

Application filed November 6, 1917. Serial No. 200,549.

To all whom it may concern:

Be it known that I, ANDREW W. GRAHAM, a citizen of the United States, residing at Buffalo, in the county of Erie and State 5 of New York, have invented certain new and useful Improvements in Matches and Packets Therefor, of which the following is a specification.

This invention relates to matches and 10 packets therefor.

It is a well known fact that the ordinary paper or fiber match which is put up in packets and torn off one at a time for striking presents many defects owing to the importance of properly protecting it from 15 weather, its liability to break when an attempt is made to strike it and various other cases. One important object of the present invention is to provide an improved form 20 of match and packet therefor wherein the action of drawing the match from its packet will effect its lighting.

Another important object of the invention is to provide an improved form of match 25 and packet therefor wherein each match is held in an individual water-proof holder.

A third important object of the invention is to provide such an arrangement of match and packet therefor as will permit a 30 thin and flexible match to be used, the striking of the match being effected while the stem is under tension.

With the above and other objects in view, as will be hereinafter apparent the invention 35 consists in general of certain novel details of construction and combinations of parts hereinafter fully described, illustrated in the accompanying drawing, and specifically claimed.

40 In the accompanying drawing, like characters of reference indicate like parts in the several views, and:—

Figure 1 is a perspective view showing an 45 individual match packet and match as constructed in accordance with this invention.

Fig. 2 is a similar view showing the match in the act of being drawn out of the packet and struck.

Fig. 3 is a longitudinal section through 50 such an individual packet.

Fig. 4 is a cross section through the match and packet.

Fig. 5 is a perspective view showing a sheet of such packets put up in such manner 55 that the matches and packets may be separated into individual packets.

Fig. 6 is a plan view of one of the packet covers as used in the sheet shown in Fig. 5.

In carrying out the object of the invention a pair of paper strips 10 are provided 60 each of which has a longitudinally extending central bulged portion 11, the edges of the paper strips being held together by any suitable adhesive material. With the bulged portion of each strip adjacent one end is 65 a friction strip 12 of the ordinary material such as is found on the outside of safety match boxes and the like. The ends of the strips 10 adjacent the friction strips 12 embrace the butt end of a match stem 13 which 70 is preferably made of some flexible material such as stout paper. This stem 13 passes between the strips 12 and is provided with an ordinary match head 14. Adjacent the strips 12 is a row of perforations 75 15.

Now these strips may be made up individually as shown in Figs. 1 to 4 or they may be made in sheets, the individual packets being separated by perforated lines 16. It will be obvious that a water-proofing of paraffin or the like may be applied to the exterior of either the sheet or the individual packet and that the match stem 13 may be impregnated with paraffin in addition. By this means a perfectly water-tight and moisture-proof packet is formed so that the match is at all times kept in proper condition for striking. When it is desired to strike the match the opposite ends of the packet are grasped as shown in Fig. 2 and a 90 sharp pull is given. This results in the breaking of the strips along the perforation lines 15 and the quick withdrawal of the flexible match under tension. This causes the head to pass between the strips 12 and ignites the match as it is drawn out of the packet. Of course when the packets are put up in sheets, as in Fig. 5, it is necessary 95 to tear off one individual packet from the sheet as may be easily done by reason of the perforations. It will be obvious that this 100 arrangement permits of a variety of uses, as for instance the individual packets may be banded, each beneath the band of a cigar or box of cigarettes or the matches may be 105 sold in boxes separately. It will also be obvious that the device may be used as an advertising device since the exterior may be printed with any desired design or words to this effect. Furthermore it is to be seen 110 that on account of the action of lighting the match being that of a quick pull both the

match and the packet may be made of much thinner material than is possible where it is necessary to strike the match by a sidewise blow against the friction surface. Thus 5 great economy can be effected.

There has thus been provided a simple and efficient device of the kind described and for the purpose specified.

It is obvious that many minor changes 10 may be made in the form and construction of the invention without departing from the material principles thereof. It is not therefore desired to confine the invention to the exact form herein shown and described 15 but it is wished to include all such as properly come within the scope claimed.

Having thus described the invention, what I claim as new, is:—

1. A combined match and packet consisting of a pair of strips having longitudinally extending oppositely disposed bulged portions, a match having a flexible stem, the butt of said match being secured between

the strips at one end of the container, said strips being weakened adjacent the end 25 to which the butt is secured and friction surfaces within said strips adjacent the weakened portion.

2. The combination with a match packet consisting of a multiplicity of individual 30 water-proof cells separated one from the other by weakened lines and having a transverse weakened line adjacent one end of each, of matches having stems provided with butts fixed in the ends of said cells adjacent 35 the transverse weakened line and having their heads loosely held in the opposite ends of said cells, and friction surfaces within each cell on the side of the respective weakened line opposite the said butts. 40

In testimony whereof I affix my signature in the presence of two witnesses.

ANDREW W. GRAHAM.
